(57) **CLAIM**

The ornamental design for a digital drum set, as shown and described.

DESCRIPTION

FIG. 1 is a perspective view of a digital drum set showing our new design;

FIG. 2 is a front view thereof;

FIG. 3 is a back view thereof;

FIG. 4 is a side view thereof;

FIG. 5 is the side view opposite to FIG. 4;

FIG. 6 is a top view thereof; and,

FIG. 7 is a bottom view thereof.

The broken lines of the figures depict environment of the digital drum set and form no part of the design.
